DOWELING HOLE SPOTTING TOOL

Charles O. Rayl, Sr., Seattle, Wash.

Application April 28, 1952, Serial No. 284,843

5 Claims. (Cl. 33—180)

1

This invention relates to devices for spotting drill holes in wood and other surfaces, and more particularly concerns a novel tool by which doweling holes may be located on one jointed surface in precise registry with complementary doweling holes already formed in the mating jointed surface. The invention is herein illustratively described by reference to the preferred form thereof as applied to the problems of forming doweled joints in the manufacture of furniture and other wooden articles, but it will be understood that the invention is not necessarily restricted in regard to the details of form nor with respect to the application for which the tool is primarily intended.

The procedure perhaps most commonly used for locating and marking the drill holes for doweled joints is to measure off and mark with a pencil on both jointed surfaces the desired corresponding distances of the holes from true reference faces and edges of the boards or parts. Theoretically, of course, this procedure is unimpeachable if perfectly executed but as a practical matter errors are often made even with the exercise of greatest care, and as a result the doweling holes will either not line up with sufficient accuracy for the parts to fit together at all, or if they do go together, their true faces and edges, instead of being flush, will often be offset one from the other and require a considerable amount of sanding down and finishing in order to produce the appearance of a precision joint. Even more serious difficulties are encountered in spotting the locations of doweling drill holes when the jointed surfaces are curved or irregular instead of being flat planar surfaces with straight reference edges.

Large furniture factories and other woodworking establishments which can afford or necessarily require fairly elaborate tooling provisions for their more or less standardized production run work frequently handle their doweling problems by means of multiple arbor drill presses and special work holding jigs. With elaborate equipment of this nature available it is readily possible to produce precision doweled joints without regard to the limitations of manual skill. However, in the shop of the hobbyist, in the ordinary woodworking or cabinet maker's shop, and even for specialized applications in large furniture making establishments and the like, doweled joints are necessarily made without benefit of multiple arbor drilling equipment or preset drilling jigs. The present invention provides a precision tool of a simple, inexpensive, compact and

2

conveniently used nature for application in these instances. The invention is not necessarily limited to woodworking, however, because the use of doweling also occurs in fabricated structures using various metals and other materials besides wood. The invention applies in any situation wherein it is desired to locate a point in one of two mating surfaces concentric with an existing hole or bore in the other surface with the parts aligned to each other in the desired ultimate positional relationship.

The present invention is based on the concept of drilling a set of doweling holes in one of the mating surfaces and inserting in each of these holes a pointed instrumentality which faces outwardly therefrom so as to punch or indent the joint surface of the other part when the two parts are brought together preliminarily under pressure. The doweling hole marks thus formed in the second part will then be located with considerable accuracy provided the marking points are truly coaxial with the first set of holes supporting them. Moreover, the technique is applicable with equal accuracy to curved or irregular joint surfaces as well as flat or planar ones.

A further object of the present invention is a doweling hole spotting tool capable of producing a well defined and sufficiently deep and wide, aptly shaped spotting indentation in a wood surface, for example, which functions reliably for leading the drill bit into the wood in the precise location desired. In order to produce a lead hole of this character considerable pressure of the tool's punch tip against the marking wood surface is necessary. It is thereby important, and constitutes an object of this invention, that the tool, socketed in a doweling hole in the mating joint surface, be formed in such manner that it will not be driven into the supporting wood during application of the necessary indentive pressure thereto and become so embedded as to be difficult to remove therefrom.

Still another object of the invention is a doweling hole spotting tool adapted for use in the described manner and the proper support of which, socketed in the first-drilled joint surface, does not depend critically upon the depth of the doweling hole receiving the tool if such hole exceeds a certain minimum depth. In other words the tool's punch tip is caused to project the desired distance from the supporting surface independently of the depth of the socketing bore.

Still another object is a spotting tool combination or set capable of functioning in the foregoing described manner with any of different

doweling hole standard diameters, the tool set involving a minimum number of parts and being simple and inexpensive to produce.

In its herein illustrated form, the improved doweling hole spotting device comprises a punch tip of right-conical form, and a substantially cylindrical shank projecting axially from the base of said punch tip and of materially lesser diameter than such base. Socketed in a doweling hole of corresponding diameter, the shank of the tool supports the punch tip in the first joint surface, so that the punch tip is concentric with the doweling hole and when the mating surface is pressed against the tip to form the spotting indentation therein, the tool will not be driven into the supporting wood under the pressure exerted. The annular base of the punch tip surrounding the rim of the supporting hole distributes the pressure over a substantial area on the first surface and thereby provides ample support preventing that occurrence. In combination with such a tool, the invention further comprises one or more shim tubes removably fitted to the shank of the tool for increasing the effective diameter thereof to fit larger standard size doweling holes. In one instance the outside diameter of the shim tube is sufficiently smaller than the diameter of the base of the conical punch tip that the latter continues to serve as a stop preventing sinking of the tool into the wood under pressure whereas in alternative illustrated forms an enlarged annular stop surrounding the shank of the tool next to the base of the punch tip increases the effective diameter of the latter in order to accommodate still large shim diameters corresponding to larger doweling holes. This annular stop may be in the form of a separate washer or of an annular flange fixed on the end of a shim tube upon which still larger shim tubes may be applied if desired.

These and other features, objects and advantages of the invention including certain details of the preferred forms thereof will now become more fully evident from the following description based upon the accompanying drawings.

Figure 1 is a perspective view, showing the parts of a spotting tool combination set in accordance with the invention, with the parts being disassembled one from another.

Figure 2 is a perspective view, illustrating an optional part which may be used in conjunction with the basic tool element of the set shown in Figure 1.

Figure 3 is a sectional view showing one application of the basic tool element in the set.

Figure 4 is a similar view showing application of the same tool element in conjunction with the shim tube of Figure 2.

Figure 5 is a similar view showing application of the same basic tool element in conjunction with a combined annular stop and shim tube combination.

Figure 6 is a similar view wherein additional successively larger shim tubes are added to the combination of Figure 5.

Figure 7 is a similar view illustrating a modification of the combination set applied as in Figure 5.

Figure 8 is a perspective view, with parts broken away, illustrating application of the invention to the spotting of doweling holes in straight planar jointed surfaces.

Figure 9 is a similar perspective view showing the jointed parts with doweling pieces inserted.

preparatory to final joining of the parts with adhesive.

Figure 10 is a top view illustrating application of the invention to the spotting of doweling holes in curved jointed surfaces.

Figure 11 is a transverse sectional view illustrating the application of a removing tool by which a tubular shim of the tool may be retracted easily from the supporting hole in case it tends to become stuck therein.

Referring to Figure 1, the basic tool or the basic element of the tool set is the spotting tool 10 comprising the right-conical punch tip 12 and the cylindrical shank 14 projecting axially from the base of such punch tip and being of materially lesser diameter than such base. In accordance with the preferred shape and dimensions of this tool for ordinary woodworking applications, the shank diameter is slightly under a quarter of an inch which is normally the smallest size doweling used in doweled joints. The length of the shank is approximately one inch. The cone angle of the punch tip is approximately 90 degrees and the diameter of its base is $\frac{3}{8}$ of an inch, the punch member work-indenting tip portion comprising the preferably pointed cone apex and the punch member base comprising the preferably planar or flat cone base 12'. It is obviously desirable that the punch tip 12 be of a hard metal such as tool steel or at least cold-roll steel whereas the shank which undergoes no wear to speak of may be of mild steel, if desired.

The second main element of the spotting tool set in its form shown in Figure 1 is the combined spacer shim and stop assembly 16 comprising the cylindrical spacer tube 18 removably fitted to the tool shank 14, and the transverse annular end flange 20 fixed upon one end of the spacer tube 18. In the example indicated, a sufficiently snug yet sliding fit between the spacer tube 18 and the shank 14 is achieved when the diameter of the shank is 0.245 of an inch and the inside diameter of the tube is 0.250 of an inch. The outside diameter of this tube is made to correspond with a next larger standard drill diameter, such as approximately $\frac{3}{8}$ of an inch. The annular stop flange 20 is typically $\frac{1}{8}$ of an inch thick and $\frac{3}{4}$ of an inch outside diameter. The thickness and diameter dimensions of the stop flange are not critical, however, and have no necessary direct relationship to the doweling hole sizes, as will appear.

Preferably, however, the diameter of the stop flange 20 exceeds by an appreciable margin the outside diameter of the largest spacer shim to be used in conjunction with the combination tool element 16, so that such flange serves as a stop in the same manner in all such combinations. Thus in the example a first larger shim tube 22 is provided to slidably fit upon the spacer tube 18, while a second larger shim tube 24 is provided to slidably fit upon the outside of the shim tube 22. The outside diameter of the tube 24 corresponding to the largest doweling size for which the illustrated spotting tool set is intended to be used, is approximately $\frac{5}{8}$ of an inch, which is still appreciably less than the outside diameter of the stop flange 20, or $\frac{3}{4}$ of an inch. The outside diameter of the intermediate size shim tube 22 is approximately one-half inch. In actual machined dimensions, however, the desired sliding fit between the several shim tubes is achieved by establishing a 0.005 of an inch difference between the diameters of contacting cylindrical surfaces. Accordingly the outside

diameter of the shim tube 18 is actually 0.370 of an inch, the inside diameter of shim tube 22 is 0.375 of an inch, the outside diameter of shim tube 22 is 0.495 of an inch and the inside diameter of shim tube 24 is 0.500 of an inch. Preferably the shim tubes 18, 22 and 24 are all of equal length, corresponding to the length of the tool shank 14, so that a doweling hole drilled deep enough to accommodate one such element will accommodate all, and also in order to minimize the length of metal in any element to a value not greater than that needed for establishing stable socketing of the tool in a doweling hole, which is, and should be, the same in all instances.

If doweling is used of a size intermediate the diameters of the shank 14 and first shim tube 18, a further element may be added to the tool set shown in Figure 1, namely the straight cylindrical shim tube 26 shown in Figure 2. The inside diameter of this optional shim tube is equal to that of the shim tube 18, whereas its outside diameter is approximately $\frac{1}{16}$ of an inch and is less, therefore, still, by an appreciable margin, than the diameter of the base of the conical punch tip 12, or $\frac{1}{8}$ of an inch, so that when these two parts are assembled together the marginal portion of the conical tube base will function as a stop surface, as desired.

Figure 3 illustrates the use of the basic tool element 10 as the spotting tool in conjunction with doweling of the smallest size for which the tool set is intended to be used. In this instance a doweling hole D of a depth greater than the length of the tool shank 14 has been drilled into the body of the first wooden part P1 and the shank is socketed in the bore. The base or under side of the conical punch tip 12 then rests against the jointed surface S1 of the part P1. The part P2 having the mating jointed surface S2 is then pressed in the direction of the arrow against the tool point, with the parts properly aligned in their intended relative positions for the joint. As a result of the pressure applied upon the tip of the tool by the part P2 its jointed surface S2 receives a distinct and well defined indentation of conical form at the proper location for drilling a doweling hole in accurate coaxial registry with the existing doweling hole d in the basic part P1. A well defined spotting indentation in the surface S2 is achieved by a moderate pressure corresponding, for instance, to that sufficient to produce penetration of the punch tip 12 half its length or depth into the surface S2, as illustrated.

In Figure 4 the basic tool 10 is used in combination with the optional shim tube 26 (Figure 2) for purposes of spotting $\frac{1}{16}$ of an inch doweling holes as in the manner described in connection with Figure 3.

In Figure 5 the basic tool 10 is used in conjunction with the combined stop and shim tube 16 for $\frac{3}{16}$ of an inch doweling holes. In this case the under side of the annular stop flange 20 rests against the jointed surface S1, to prevent the tool sinking into the wood under pressure from the mating surface S2. The annular flange 20 is relatively thin, however, so that the tip of the tool 10 does not stand out from the surface S2 much farther than it did in Figures 3 and 4, when no additional or enlarging stop element was used. It is desirable to minimize the projection of the punch tip from the supporting surface, so that the mating joint surfaces S1 and S2 will approach closely together when the spotting

indentations are being formed, and thereby facilitate more accurate alignment of the mating parts in their intended joined relative positions under these conditions.

5 In Figure 6 the combination of Figure 5 is used in conjunction with two additional shim tubes 22 and 24, in order to accommodate the largest size holes for which the set illustrated in Figure 1 is intended to be used. In this case, of course, the outer margin of the annular stop flange 20, projecting beyond the outside face of the largest shim tube 24, rests upon the jointed surface S1 and functions as the tool stop preventing the same from sinking into the wood and becoming difficult to remove.

10 In Figure 7 a modified version of the combination shown in Figure 5 is illustrated. In this case the dimensions and shape of the various parts are the same as in the previous form, but the annular stop flange is formed as a separate washer 20' detachable from the shim tube 18'. In general respects, however, the two arrangements produce the same results and operate in the same manner. The advantage of the arrangement of Figure 5 over that of Figure 7, of course, lies in the combining of parts 20 and 18 so as to minimize the number of parts of the tool set which must be handled, which because of their numbers may tend to become misplaced or lost if laid carelessly about.

15 Figure 8 illustrates application of the invention to the practical case of spotting the doweling holes for a doweled joint between straight planar ends of two wooden boards B1 and B2. The doweling holes d1, d2, d3 are first drilled into the jointed ends of the first board B1 to receive the spotting tool combination of Figure 5, for instance, in each hole. The boards are then placed with their true faces down against a flat 20 horizontal supporting guide surface h, and with their true edges against an adjoining vertical guide surface v. Thus aligned by reference to the guide surfaces, the boards are moved together under pressure to form a set of indentations in 25 the jointed end of the board B2 precisely opposite the existing doweling holes d1, d2, d3 in the board B1. Thus when the complementary set of doweling holes is drilled in the board B2 and doweling pieces dp are inserted as in Figure 9, 30 a true and perfect doweled joint is achieved.

35 The normally exacting and complex operation of spotting doweling holes in curved jointed surfaces S1' and S2', as in Figure 10, is also easily accomplished by use of the invention inasmuch as no complicated measurements for locating the holes in one jointed surface precisely in registry with those in the other are necessary. Thus all 40 the former difficulties of measuring along curves or going to other inconvenient lengths to obtain a perfect joint are avoided in simple expeditious manner. The two parts B1' and B2' having the curved jointed surfaces are simply brought together in the manner illustrated in Figure 8 or a comparable manner, depending upon the nature 45 of the true surfaces of the boards which are to be used for purposes of guidance, and the punch tips 12 of the spotting tools will produce the desired drilling lead holes in the surface S2'. Preferably and as illustrated in the figure, the doweling holes in part B1' are counterbored slightly 50 in order to provide a better seat for the stop flange 20 than a curved surface provides.

55 Figure 11 illustrates the application of a convenient retracting tool T by which the tubular 75 shim 18 may be removed from the doweling hole

after use in the event it tends to become stuck therein. The same tool may be used to remove the outside shim tube of any combination of tubes illustrated in Figures 4 to 6, inclusive. This tool simply comprises a shank portion T1 terminating in a short hook T2, which is used to engage the lower end of the shim tube 18 and draw it from the supporting hole *d* in obvious manner.

While it has been said that the invention is illustrated in its preferred form, it should also be noted that certain variations or modifications may be made in the detailed shapes or forms of various parts and in respect to the materials and dimensions thereof, number of shim tubes used, etc., without departing from the underlying concepts involved. For example, the punch tip 12 is described and illustrated as being a right-conical body, and the tool shank 14 is described and illustrated as being a circular cylindrical body. In this form the parts are perhaps more economically machined or otherwise produced, and tend to produce the optimum shape of spotting indentation in the second surface S2, as well as socketing most satisfactorily in a cylindrical doweling hole *d* in the first surface S1. However, it will be obvious that other tapered or pointed forms for the punch tip may be used if desired, of circular or other cross-sectional form, and that the function of supporting the punch tip in concentric relation to the doweling hole *d* performed by the shank 14 may be accomplished with shanks of other forms than a circular cylindrical form. The possible variations in these respects, as well as in others concerning other parts of the tool combination, will be obvious to those skilled in the art. Accordingly it is intended that the invention as defined in the following claims should be construed with a view to giving full effect and scope to the principles involved which are illustrated and described in the foregoing specification by reference to the preferred examples thereof.

I claim as my invention:

1. The doweling hole spotting tool combination comprising a punch having a right-conical head and a substantially cylindrical shank projecting axially from the base of said conical head and of materially lesser diameter than said base, a shim tube removably fitted to said shank for increasing the effective diameter thereof, and a relatively thin annular stop member removably fitted to said shank, of materially larger outside

diameter than said base and said shim, and interposed between said base and the adjacent end of said shim mounted on said shank.

2. The combination defined in claim 1, wherein the annular stop member comprises an outwardly projecting flange fixed on the end of the shim tube.

3. The combination defined in claim 2, and an additional shim tube removably fitted to the outside of the first shim tube and having an outside diameter materially less than the outside diameter of the stop member.

4. The combination defined in claim 1, and an additional shim tube removably fitted to the outside of the first shim tube and having an outside diameter materially less than the outside diameter of the stop member.

5. The doweling hole spotting tool comprising a punch having a central indenting tip adapted for pressure-indentation of work materials to be bored, a substantially cylindrical elongated shank coaxial to said tip, a stop portion projecting transversely outward from the side of said shank back of said tip adapted to seat against the face 20 of a piece of work having a dowel hole in which said shank is socketed, said shank having substantially uniform transverse dimensions adjacent said stop portion and along the projecting length of said shank, and tubular shim means 25 removably fitted to the shank of said tool and having a thin annular flange on one end, of a materially greater outside radius than the radially projecting width of the tool stop portion.
